UNITED STATES PATENT OFFICE.

MAXIMILIAN N. KOCH, OF BUFFALO, NEW YORK.

CUSPIDOR.

1,257,250.

Specification of Letters Patent. Patented Feb. 19, 1918.

Application filed June 6, 1917. Serial No. 173,218.

To all whom it may concern:

Be it known that I, MAXIMILIAN N. KOCH, a citizen of the United States, residing at Buffalo, in the county of Erie and State of New York, have invented new and useful Improvements in Cuspidors, of which the following is a specification.

This invention relates to a cuspidor which is more particularly designed for use in public places, for instance, at the side of streets, in public parks and in buildings which are generally used by the public such as depots, municipal halls &c.

It is the object of this invention to produce a cuspidor for this purpose which is simple in construction and efficient in operation, which permits of effectively depositing the sputum therein without liability of scattering the same outside of the cuspidor, which is strong and durable and not liable to be injured by rough usage nor liable to be clogged by foreign matter and which is effectively flushed by water so as to maintain the external sputum receiving surfaces constantly clean and in a sanitary condition.

In the accompanying drawings:

Figure 1 is a vertical section of a cuspidor embodying the preferred embodiment of my invention. Fig. 2 is a fragmentary vertical section, on an enlarged scale, of the apex of the deflector and adjacent parts forming parts of my improvement. Fig. 3 is a top plan view, on an enlarged scale, of my improved cuspidor.

Similar characters of reference indicate corresponding parts throughout the several views.

My improved cuspidor may be mounted in any suitable manner the means for this purpose shown in the drawings being an example and comprising a hollow upright base or pedestal 1 which is adapted to rest upon the floor or pavement 2 to which it may be secured in any suitable manner and thereby permit a water pipe 3 for flushing the cuspidor and a drain pipe 4 for carrying off the waste matter from the cuspidor to be arranged within this pedestal, thereby not only concealing the same from view so as to render the cuspidor more attractive but also protecting these pipes from interference or tampering. In its lower part this pedestal is preferably provided with a door 6 which may be controlled by a lock or key 55 which door upon being removed permits

authorized persons to gain access to the handle 5 within the pedestal which controls a valve 7 in the water pipe whereby the supply of water to the cuspidor may be turned on or shut off when desired.

In its general organization my improved cuspidor which surmounts this pedestal comprises a lower section 8 which is preferably constructed in the form of a semi-globular hollow bowl which has its concave or inner side facing upwardly, and an upper section or deflector 9 which is reduced from its lower end toward its upper end. The lower section or bowl is preferably formed integrally of cast metal with the pedestal and is provided centrally in its bottom with an upwardly projecting guard tube or collar 11 and on one side of said guard tube with a drain opening 12 formed in a downwardly projecting nipple 13 arranged on the underside of the bowl within the pedestal and connected with the upper end of the drain pipe 4 so as to communicate therewith. Adjacent to its upper edge the bowl is provided internally with an annular upwardly facing shoulder or shelf 10 which preferably slopes inwardly, as shown in Fig. 1.

The upper section or deflector of the cuspidor preferably comprises an upwardly tapering conical part 14, a lower cylindrical part 15 projecting downwardly from the lower edge of the conical part, a plurality of laterally projecting supporting lugs 16 arranged at the lower edge of the conical part, and a pocket 17 extending downwardly from the central part or apex of the deflector and opening upwardly to the upper surface of the latter. In the assembled position of the deflector its cylindrical lower part is arranged within the upper part of the bowl and its lugs rest on the shoulder 10 of the same so as to form an annular passage between the marginal part of the deflector and the marginal part of the bowl whereby the upper external surfaces of the cuspidor are placed in communication with the interior thereof, and the upper outwardly sloping surface of the conical part of the deflector is arranged in line with the upper edge of the bowl, as shown in Fig. 1.

Projecting upwardly from the central part of the bottom of the pocket 17 is a water outlet nipple 18 forming an annular space between the bore of this pocket and the periphery of this nipple. The latter may

be secured to the bottom of this pocket in any suitable manner, for instance by means of a screw joint, as shown in Fig. 2. At its upper end this outlet nipple is closed preferably by means of a cap 20 which is arranged adjacent to and substantially in line with the top of the deflector. This cap may be secured to the outlet nipple by means of a screw joint, as shown in Fig. 2, or by 5 any other suitable means. In its side this outlet nipple is provided with one or more outlet openings 19 and at its lower end the same is connected with the upper end of the water supply pipe 3 which latter extends 10 upwardly through the guard collar 11 in the bottom of the bowl.

Preparatory to putting this cuspidor in use the water supply is turned on with sufficient force to cause the water to flow from 20 the supply pipe 3 through the outlet nipple 18 and into the pocket 17 and then overflow from the top of the pocket in all directions in the form of a ring, thence over the upper conical surface of the deflector in the form 25 of a thin film or stream, thence downwardly through the annular passage between the deflector and the bowl, and thence through the outlet of the bowl into the drain pipe. The water is prevented from passing out 30 through the bore of the guard collar 11 and into the base or pedestal by making this collar sufficiently high for this purpose.

The sputum is deposited upon the conical upper surface of the deflector from which it 35 is washed downwardly into the annular passageway and to the inner side of the bowl by the film of water flowing downwardly continuously from the elevated central part of the deflector to the depressed outer part 40 thereof whereby the sputum is carried away to the drain pipe. By supplying the water at the apex of the deflector in the manner shown a continuous stream of water may be maintained for constantly flushing the deflector and bowl and at the same time reducing 45 to a minimum the liability of clogging this water outlet by foreign matter such as cigar ends or the like. By projecting the deflector upwardly beyond the upper edge 50 of the bowl any sputum which may be delivered against the same is not liable to be blown backwardly against the clothing of a person discharging the same in the event that a wind is blowing in a direction which 55 otherwise might produce this result. Owing to the upwardly tapering form of the deflector any foreign matter, such as newspapers, boxes or the like, are not likely to 60 lodge on the deflector but will either fall off onto the ground or floor and thereby leave the deflector clear of obstructions and in condition for use. Inasmuch as the upper conical surface of the deflector inclines or slopes on an angle which is in line with the 65 upper edge of the bowl any hard foreign

matter which may be thrown or deposited on the inclined surface of the deflector will roll from the latter and owing to its momentum pass outwardly beyond the upper edge of the bowl and to the ground instead of 70 lodging in the annular passageway between the deflector and bowl, thereby reducing to a minimum the possibility of clogging this passageway.

By screwing the cap 20 upwardly or downwardly on the outlet nipple 18 the flow of water from the pocket or basin 17 can be regulated so as to insure a uniform annular distribution of the water over the entire upper surface of the deflector and cause 80 thorough flushing of the same to remove any matter deposited thereon.

It will be noted that owing to the advantageous construction of this cuspidor the same is not liable to become clogged, it is 85 strong and durable so as to withstand a considerable amount of misuse to which it may be subjected, the surfaces which receive the sputum are constantly maintained in a clean and sanitary condition, and owing to the 90 simplicity of its construction the same can be produced at comparatively low cost.

I claim as my invention:

1. A cuspidor comprising a bowl provided with an internal shoulder, and a deflector 95 projecting above the bowl and provided at its lower end with a plurality of lugs resting on said shoulder.

2. A cuspidor comprising an annular upwardly opening bowl provided adjacent to 100 its upper edge with an annular internal upwardly facing shoulder, and a bowl having an upwardly tapering conical upper part which is arranged above the bowl and has its upper surface sloping in line with the upper edge of said bowl, a cylindrical lower part projecting from the large lower end of the conical part into the upper end of the bowl but separated therefrom by an intervening annular passage and supporting lugs 110 arranged on the lower edge of said cylindrical part and engaging with the shoulder of the bowl.

3. A cuspidor comprising a bowl, an upwardly tapering deflector mounted on said bowl and provided at its apex with a pocket which opens at its upper end to the upper surface of said deflector, and means for supplying water to said pocket comprising an outlet nipple mounted on the bottom of said 115 pocket and provided in its side with outlet openings.

4. A cuspidor comprising a bowl, an upwardly tapering deflector mounted on said bowl and provided at its apex with a pocket 125 which opens at its upper end to the upper surface of said deflector, and means for supplying water to said pocket comprising an upright outlet nipple mounted at its lower end centrally on the bottom of said pocket 130

and having its top closed and arranged adjacent to the top of said deflector and provided in its side with outlet openings.

5. A cuspidor comprising a bowl opening upwardly and provided in its bottom with an upwardly projecting guard collar, and on one side of said collar with a drain opening,

a drain pipe communicating with said drain opening, a conical deflector mounted on said bowl and provided at its apex with a water outlet, and a water supply pipe arranged in said guard collar and communicating with said water outlet. 10

MAXIMILIAN N. KOCH.
